To all whom it may concern:

Be it known that I, CHARLES R. CRANE, 2d, a citizen of the United States, residing at Chicago, in the county of Cook and State of Illinois, whose post office address is 836 South Michigan Avenue, Chicago, Illinois, have invented a new, original, and ornamental Design for Handwheel, of which the following is a specification, reference being had to the accompanying drawing, forming part thereof.

In the drawing:

Fig. 1 is a top view of the handwheel embodying my design.

Fig. 2 is a side view of the handwheel.

Fig. 3 is a front view of the handwheel.

I claim:

The ornamental design for a handwheel, substantially as shown.

CHARLES R. CRANE, II.
